UNITED STATES PATENT OFFICE.

LEO UNGEMACH, OF SCHILTIGHEIM, NEAR STRASSBURG, GERMANY.

DESIGN FOR A BOX.

46,353.

Specification for Design.

Patented Sept. 1, 1914.

Application filed May 26, 1914. Serial No. 841,163. Term of patent 3½ years.

To all whom it may concern:

Be it known that I, LEO UNGEMACH, a subject of the Emperor of Germany, residing at Bischweilerstrasse 72, Schiltigheim, near Strassburg, Alsace, Germany, have invented a new, original, and ornamental Design for a Box, of which the following is a specification, reference being had to the accompanying drawing, forming part thereof.

The figure is a perspective view of a box, showing my new design.

I claim:

The ornamental design for a box as shown.

L. UNGEMACH.

Witnesses:

CHARLES A. HALLEY, Jr.,

JACOB W. SCHMIDT.
